CENTER LOCATING AND SCRIBING DEVICE
Dewey Hendrix, 1306-A Salem Road, Morganton, N.C.
Filed Dec. 12, 1960, Ser. No. 75,169
4 Claims. (Cl. 33—191)

This invention relates to center locating devices and, more particularly, to an improved center locating device of the type customarily having a central hub and a plurality of radial arms mounted in the same or parallel planes for simultaneous coextensive longitudinal movement through the hub. One well known device of this type customarily employs two pairs of arms mounted for movement through the hub, the arms of each pair extending parallel to one another, but perpendicular to the arms of the other pair.

Centering devices of the type described generally above have found wide application in accurately locating the centers of objects having a cross-sectional shape which is either circular, or of other regular polygonal configuration in which the number of sides of the polygon is a multiple of four. Inherent in the heretofore known devices, however, is a lack of versatility which impairs, if not obviates, their utility for quickly and accurately locating the centers of objects having a cross-sectional shape other than as described above; e.g., an object which is irregularly polygonal, or hexagonal, in cross-section.

It is, accordingly, a primary object of this invention to provide a device of the type described which has an enhanced versatility, particularly in that it may be used to more quickly and accurately locate desired points upon various regularly polygonal work surfaces which are neither circular or have a number of sides which is a multiple of four.

Another object of this invention is the provision of a device capable of utilization upon cross-sectional shapes of irregular polygonal configuration and which have a single pair of elongated parallel sides, and more particularly which is capable of locating the center and other lines parallel to such sides.

Still another primary object is to provide a novel device of economical, compact, and durable construction which is capable of locating both the center of a work surface and, additionally, various desired radial points from such center. This is particularly beneficial, for instance, when working with a flanged object in which it is desired to locate both an axial bore and various radial bolt holes.

A more specific object is the provision upon the outer end of one or more arms of a device of the type described of a work engaging jaw or foot which is movably mounted so that it can be optionally placed in work engaging position or readily moved to an inactive location; and in which one or more radial-point locating members is slidably mounted upon an arm or arms of the device.

Still other objects and advantages of the invention will be in part evident and in part pointed out hereinafter in the following description of an illustrative embodiment of the invention, which should be read in conjunction with the accompanying drawings, in which—

FIGURE 1 is a top perspective view of a device according to the invention suspended above a circular work surface, two feet of the device being shown in a location to engage work and the remaining two feet being shown in an inactive location;

FIGURE 2 is a plan view, in reduced scale, of the device in center locating position upon the work surface shown in FIGURE 1, all of the feet of the device being shown in work engaging location;

FIGURE 3 is a side elevation of the device;

FIGURE 4 is an enlarged horizontal section taken

2

along line 4—4 of FIGURE 3 of the hub structure of the device;

FIGURE 5 is an enlarged horizontal section taken along line 5—5 of FIGURE 3 of the hub structure of the device;

FIGURE 6 is an enlarged horizontal section taken along line 6—6 of FIGURE 3 of the hub structure of the device;

FIGURE 7 is an enlarged vertical section taken approximately along line 7—7 of FIGURE 2 of the hub structure of the device;

FIGURE 8 is a horizontal section taken along line 8—8 of FIGURE 7 of the operating knob and punch of the device;

FIGURE 9 is a plan view of the device positioned upon a work surface of irregular polygonal configuration; and

FIGURE 10 is a plan view of the device positioned upon a work surface of hexagonal configuration.

Referring more particularly to the drawings, a device 20 according to the instant invention is identified in its entirety in FIGURE 1 by the numeral 12, and includes generally a central hub 14 having two pairs of arms 18, 20 and 22, 24 radiating outwardly therefrom in parallel planes, the arms 18, 20 and 22, 24 of each pair being 25 parallel to one another and perpendicular to the arms of the other pair, and all of the arms being mounted in a manner described more fully hereinafter for simultaneous coextensive longitudinal movement through hub 14. While for purposes of illustration, the instant invention is 30 disclosed as applied to and in conjunction with the well known structure thus far described, no restriction thereto is intended, for it will become apparent that other type structures—e.g., those having a greater or lesser number of radial arms—might also employ the various novel 35 teachings hereinafter discussed.

Referring now once again to the drawings, particularly FIGURES 3 through 7, it will be seen that hub 14 comprises a pair of square plates 26, 28, each of which is provided with a pair of spaced parallel slots or channels 40 30 connected by a recessed central portion 31, a central bore 32, and a notch 33 midway of each edge; the plates being secured together by screws 34 (see FIGURE 1) with the channels 30 of each extending normal to channels 30 of the other and with portions 31, bores 32 and 45 notches 33 in alignment. The outer face of one of the plates, illustratively that of plate 28, constitutes the base 35 of the hub 14 thus formed.

Slidably mounted in channels 30 parallel to and above base 35 of hub 14 are arms 18, 20, 22, 24, the inner face 50 of each of which is provided with notches or teeth 36. In order to impart simultaneous coextensive longitudinal movement to the arms, a single driving mechanism in engagement with the teeth 36 of each arm is provided within hub 14. This mechanism includes a sleeve or spindle 38 55 rotatably mounted within aligned bores 32 of hub 14 and projecting above at its upper end beyond said bores. The lower inner end of spindle 38 mounts a pinion or gear 39 received within sunken portions 31 of hub 14 and of sufficient diameter and height to engage the teeth 36 60 of each arm, and the projecting upper end of the spindle is contained within the axial bore 48 of an operating knob 42 located upon the upper surface of hub 14. It will be noted from FIGURE 7 that knob 42 is provided with a hollow interior portion or cavity 43, the purpose of which 65 will be discussed hereinafter. Both gear 39 and knob 42 are rigidly secured to spindle 38 by any suitable means; illustratively, gear 39 may be pressed thereon, and knob 42 may be secured by means of set screws 44, as shown. It is apparent that with the construction described, rotation of knob 42 will simultaneously impart rotation to gear 39 and thereby cause the arms 18, 20, 22, 24 to 70

move coextensively in unison in the direction of the longitudinal axis of each.

In order to lock the radial arms in any desired longitudinal position, an annular member 46 is secured atop hub 14, as by means of screws 48, with its inner surface in bearing contact with the outer shaft surface of knob 42. Member 46 is provided with a radial bore 47 (see FIGURE 6) to permit access to set screws 44, and with a threaded outer surface which is engaged by the complementary inner threaded surface of locking ring 54, as best shown in FIGURE 7. Beneath the lower surface of locking ring 54 are the upper ends of a plurality of pin members 58, 60, 62, 64 which are mounted for vertical reciprocation within bores 66 provided therefor in plate 26 of hub 14. The lower ends of pins 58, 60 rest upon arms 18, 20, respectively, and the lower ends of pins 62, 64 rest upon arms 22, 24. The length of pins 58, 60 is somewhat greater than the length of pins 62, 64 so that the upper ends of all the pins lie within the same plane, which is within the path of vertical movement of ring 54. Thus, when locking ring 54 is rotated in a direction to move it downwardly, the lower surface thereof will abut the upper ends of the pins and urge the lower ends downwardly against the arms they contact, simultaneously locking all of the arms against movement. When locking ring 54 is rotated in the opposite direction and thus moved upwardly out of contact with pins 58, 60, 62, 64, the lower ends of these numbers will merely rest upon their respective arms, and exert no locking force thereagainst.

It is contemplated that the desired rotative movement of both knob 42 and locking ring 54 will be achieved manually, and to assist in this regard the outer surfaces of both of these members may be knurled or otherwise suitably roughened, as indicated at 74.

As noted heretofore, knob 42 is provided with a hollow interior or cavity 43, and also with an axial bore 40. Extending through bore 40 and slidably mounted within spindle 38 is a punch 82 having an annular groove 80. Cavity 43 in knob 42 accommodates the two halves of a leaf spring 78, best seen in FIGURES 7 and 8, which engage groove 80 and thus resiliently maintain punch 82 in a normally upward position with the upper end thereof projecting above knob 42 and the lower end enclosed within spindle 38, as shown. It will be apparent that when in its normally upward position, punch 82 will not project beyond the lower surface of hub 14 or otherwise interfere with the positioning of device 12 upon a work surface. When the center of the work has been located, however, in a manner described more fully hereinafter, the punch may readily be depressed as by means of a hammer blow upon its projecting upper end, so that its lower end will strike the work surface and permanently record the location of the center.

Referring now particularly to FIGURE 1, upon the outer end of each radial arm of device 12 there is rigidly secured, as by means of rivets 86, a bracket 84 having a vertical planar face 85. Extending outwardly from face 85 of each bracket 84 are a plurality of pins 88, 90, 92, and mounted upon each pin 92 for pivotal movement in a vertical direction (as indicated by the two-headed arrows in FIGURE 1) is a foot member 94 of generally L-shaped configuration. Pins 88, 90, serve to both delineate the opposite extreme pivotal locations of each foot 94, and to maintain each foot in one or the other of such locations. Thus, each pin 90 defines the extreme downward pivotal location of a foot 94, in which position the foot is properly situated to engage the work, with its major leg 95 being disposed beneath the plane of base 35 of hub 14 and extending radially inwardly as illustrated by the feet upon arms 18, 20 in FIGURE 1. The length of the major leg 95 of each foot 94 is such that when positioned as described the inner end thereof will be adjacent bore 32 when the arms of the device are fully retracted,

which permits utilization of the device upon work of extremely small diameter. When it is desired to move a foot 94 to an inactive, non-work engaging location above the plane of base 35, this may be quickly and easily accomplished merely by manually pivoting the same upwardly about pin 92 until it engages and rests upon its pin 88, as illustrated by the feet upon arms 22, 24 in FIGURE 1, and as shown in FIGURE 3. It will be noted that when a foot 94 is in this upward position, it is disposed entirely above the plane of base 35 of hub 14 and extends radially outwardly, as shown. The provision of foot members which may be quickly moved from an active, work engaging location to an inactive, non-work engaging location—and vice versa—is deemed to be a highly significant and novel feature of the instant device, which contributes markedly to its enhanced versatility as will be noted in the subsequent discussion herein of the operation of the device.

Another highly significant and related feature is the provision of means for ascertaining upon a work surface the location of various points and/or lines radially spaced from the center of hub 14. This may be accomplished by locating blocks 96 which, as best seen in FIGURES 1 and 3, are each provided with an opening 98 extending horizontally therethrough for reception of and slidable mounting upon an arm of the device, and a vertical bore 100 through a projecting portion 101 thereof. When the blocks 96 are mounted upon the arms of the device, as shown, they are disposed entirely above the plane of base 35 of hub 14 and the projected axis of the bore 100 of each will intersect a radius between a foot 94 and the axis of punch 82. Therefore, when device 12 is centered upon a work surface, a desired radius may be drawn by the simple expedient of inserting a stylus or the like in the bore 100 of any block 96, and by sliding that block along its arm between bracket 84 and the inner face of notch 33 while maintaining the stylus in contact with the work surface. In order that the location of various points upon such radius might be determined if desired, the arms 18, 20, 22, 24 may be provided along their lengths, preferably upon their upper surfaces, with identical indicia of measure 103 properly correlated to the shape of the block so that the linear distance of the axis of each bore 100 from punch 82 can be quickly ascertained. Additionally, it is preferred that each block 96 be provided with a locking screw 102 extending therethrough and bearing upon the arm received within its opening 98, so that each block can be quickly locked in place or released for sliding movement merely by rotation in the appropriate direction of its screw 102. To facilitate the manual rotation of screws 102, the outer surface of each may be knurled as at 74, if desired.

Having now described in detail the structure of a device according to the instant invention, a few illustrative modes of operation and advantages thereof will be noted. When the device is employed to find the center of an object having a cross-section shape which is circular, or of other regular polygonal configuration in which the number of sides of the polygon is a multiple of four, each foot 94 is positioned in its lower location abutting stop-pin 90, the device is placed with base 35 of hub 14 resting upon the work, and the arms 18, 20, 22, 24 simultaneously and coextensively moved by rotating knob 42 until the inner end of each foot 94 engages the edge of the work. Punch 82 will then be situated over the center of the work, and such center may be marked by striking the upper end of punch 82 with a hammer or the like.

A more detailed explanation of the operation of the device in thus locating the center of work of circular or other cross-sectioned shape noted above is not deemed necessary, since such operation is materially the same as that of various rigid foot devices heretofore known and now in general usage. Discussion may therefore

be now directed to other functions which a device embodying the invention is capable of performing, and to its mode of operation in conjunction with work having a cross-sectional shape other than as noted above.

Thus by reference to FIGURES 1 and 2, it will be apparent that once the device 12 is centered upon work of circular cross-section, for instance the work 106 shown, the location of any desired radial point may be easily determined; an illustrative instance when this capability is extremely desirable, as noted heretofore, is when seeking to locate both an axial bore and various radial bolt holes in a flanged object. In locating the desired radial points, preferably locking ring 54 is first rotated in a direction to bear against pins 58, 60, 62, 64 and thereby simultaneously secure arms 18, 20, 22, 24 against accidental displacement. Blocks 96 may then be moved a predetermined distance—which may, but need not necessarily be the same for each—along their respective arms, as indicated by indicia 103, a stylus or the like inserted within the bores 100, and the point or points marked upon the work surface. If desired, any or all of blocks 96 can then be locked to their arms by means of screws 102, and device 12 rotated bodily in the plane of the work so as to determine another set of points located the same radial distance, but circumferentially spaced, from the former. It will also be noted that by holding a stylus within a bore 100 while bodily rotating the device 12, any number of circles concentric with the outer edge of work 106 might be inscribed.

The utility of the device with respect to work surfaces which are irregularly polygonal, or regularly polygonal, but having a number of sides not a multiple of four, is illustrated in FIGURES 9 and 10, respectively, to which reference is now made.

In FIGURE 9, device 12 is shown properly situated upon work 108 having a single pair of parallel sides, but of irregular polygonal cross-section, such as a plank, beam, or the like. Two of the feet 94—illustratively those upon arms 18, 20—are in their upward non-work engaging position, thus permitting base 35 of hub 14 to rest upon work 108 and the other two feet 94, which are in their downward position upon arms 22, 24, to engage opposite parallel edges. When thus situated, a center line may be inscribed along the entire length of work 108 by locking the arms against movement (if desired), holding punch 82 in depressed condition or inserting a stylus in the block 96 upon either arm 18 or 20, and sliding the device 12 longitudinally of the work. Additionally, by utilizing blocks 96 upon arms 22, 24 in the manner previously described, any number of lines parallel to and a predetermined distance from such center line and the parallel edges of work 108 might be inscribed.

It should be apparent that a device having work engaging feet not readily movable into an inactive location could not be utilized in the manner shown in FIGURE 9, since those feet upon the arms extending longitudinally of the work would prohibit placement of base 35 upon the work surface, and would make it impossible to bring the other feet into contact with the parallel edges. The same limitation frequently restricts the utility of known rigid foot devices in conjunction with a work surface of regular polygonal cross-section in which the polygon has a number of sides which is not a multiple of four.

Thus, the center of an object of hexagonal cross-section, such as object 110 in FIGURE 10, could not be determined with a rigid foot device by placing two feet thereof in contact with opposite parallel sides, since the remaining two feet—instead of the base of the hub of the device—would rest upon the surface of the work and prohibit such placement. Rather, it would be necessary to resort to the obviously undesirable expedient of attempting to balance two feet upon the points of the work, so that the remaining feet would extend beyond the periphery thereof. With the instant device, however, the center of work 110

can be quickly and accurately located, and various desired points and lines inscribed thereon, by pivoting the feet upon arms 18, 20 into inactive position, placing base 35 of device 12 upon the work surface, bringing feet 94 upon arms 22, 24 into contact with opposite parallel edges and locking the arms in place, and sliding device 12 across the work until opposite points of the hexagonal shape lie directly beneath bores 100 and indicia 103 indicates that blocks 96 are equidistant from punch 82. When the device is thus situated, as shown in FIGURE 10, the center of work 110 and various radii therefrom can then be marked by means of punch 82 and blocks 96, as discussed heretofore.

Similar advantages of the instant device exist with respect to locating the center of a decagonal shape, to directly inscribing the minor axis of an elliptical shape, and in various other usages which will be apparent to those skilled in the art.

In the drawings and specification there has been set forth a preferred embodiment of the invention and, although specific terms are employed, they are used in a generic and descriptive sense only and not for purposes of limitation, the scope of the invention being defined in the claims.

25 25 That which is claimed is:

1. A center locating device comprising a hub having a base adapted to be positioned upon a work surface and a bore adapted to receive center marking means intersecting said base, said hub having a plurality of channels extending therethrough about said bore generally parallel to the plane of said base, elongated arm members slidably mounted within said channels and extending beyond the ends thereof outwardly from said hub, means on said hub interconnecting said arm members for simultaneous movement through said channels, foot members carried by said arm members, said foot members normally extending from said arm members below the plane of said base of said hub and defining for any given position of said arm members relative to said hub the circumstance of an imaginary circle having its center in alignment with the axis of said bore of said hub, said foot members being movably mounted by said arm members for free movement relative thereto through the plane of said base of said hub whereby said foot members are alternatively positionable so as to be disposed when desired entirely above the plane of said base, stop means on said arm members intersecting the paths of free movement of said foot members and defining said first mentioned locations thereof below the plane of said base, and radial-point locating members slidably mounted upon said arm members for movement therealong between said foot members and said hub, said locating members being disposed entirely above the plane of said base.

2. A center locating device comprising a hub having a base adapted to be positioned upon a work surface and a bore intersecting said base adapted to receive center marking means, said hub having two pairs of channels extending therethrough parallel to the plane of said base, the channels of each of said pairs extending on opposite sides of said bore parallel to each other and normal to the channels of the other of said pairs, elongated arm members slidably mounted in said channels and extending beyond the ends thereof, means on said hub interconnecting said arm members for simultaneous coextensive movement through said channels with the arms of each of said pairs moving in opposite directions to each other, foot members pivotally mounted upon opposite ends of said arm members of each pair of parallel arm members, the paths of pivotal movement of said foot members intersecting the plane of said base of said hub whereby said foot members are positionable in first locations extending below the plane of said base and alternatively in second locations disposed entirely above the plane of said base, stop means upon said arms intersecting the paths of pivotal

movement of said foot members and defining said first locations thereof below the plane of said base, and radial-point locating members slidably mounted upon said arm members for movement therealong between said hub and said foot members, said locating members being disposed entirely above the plane of said base.

3. A device as in claim 2, wherein there are openings communicating said channels and the surface of said hub opposite said base, and further including pin members slidably mounted within said openings with the lower ends thereof in engagement with said arm members within said channels and the upper ends thereof projecting above said surface of said hub, and means on said hub for exerting simultaneous downward forces upon the upper ends of said pins to urge said pins into locking engagement with said arm members and thereby lock said arm members against movement through said channels when desired.

4. A center locating device comprising a hub having a horizontal base adapted to be positioned upon a work surface and a centrally located vertical bore intersecting said base, said hub having two pairs of channels extending therethrough parallel to the plane of said base equidistant from said bore, the channels of each of said pairs extending parallel to each other on opposite sides of said bore and normal to the channels of the other of said pairs, elongated arm members slidably mounted within said channels and extending beyond the ends thereof outwardly from said hub, means on said hub for moving said arm members simultaneously and coextensively relative to said hub through said channels, said means including an operating knob having an axial bore and a hollow interior portion communicating with said axial bore, said knob being rotatively mounted upon said hub with said axial bore in alignment with said central bore of said hub, a center punch extending through said central bore of said hub and said axial bore of said knob and having an annular notch intermediate its length, a leaf spring mounted within said hollow portion of said knob and engaging said notch of said punch, said spring mounting said punch for reciprocatory movement through said bores

5
